US00D555230S

(12) **United States Design Patent** (10) **Patent No.:** **US D555,230 S**
(45) **Date of Patent:** **** Nov. 13, 2007**

(54) **SPOUT PORTION**

(75) Inventors: **Douglas A. Kemp**, North Ridgeville, OH (US); **Christopher Jon Gilbert**, Moreland Hills, OH (US)

(73) Assignee: **Moen Incorporated**, North Olmsted, OH (US)

(**) Term: **14 Years**

(21) Appl. No.: **29/265,619**

(22) Filed: **Sep. 5, 2006**

(51) **LOC (8) Cl.** **23-01**

(52) **U.S. Cl.** **D23/249; D23/255**

(58) **Field of Classification Search** D23/238-257; 4/675-678; 137/801

See application file for complete search history.

Primary Examiner—Louis S. Zarfas

Assistant Examiner—Gregory Andoll

(74) *Attorney, Agent, or Firm*—Calfee, Halter & Griswold LLP

(57) **CLAIM**

The ornamental design for a spout portion, as shown and described.

DESCRIPTION

FIG. 1 is a perspective view of a spout portion of the new design;

FIG. 2 is a left side elevational view of the spout portion of FIG. 1;

FIG. 3 is a front elevational view of the spout portion of FIG. 1;

FIG. 4 is a top plan view of the spout portion of FIG. 1;

FIG. 5 is a right side elevational view of the spout portion of FIG. 1; and

FIG. 6 is a rear elevational view of the spout portion of FIG. 1; and,

FIG. 7 is a bottom plan view of the spout portion of FIG. 1.

The portions of the Figures shown in broken lines are not part of the claimed design and are for illustration only.

1 Claim, 2 Drawing Sheets
